FOUNTAIN PEN

Anthony Lo Curto, Brooklyn, N. Y.

Application February 6, 1937, Serial No. 124,408

4 Claims. (Cl. 120—49)

The invention relates to fountain pens and has for one of its main objects to provide a fountain pen which has no parts which must be removed before the pen is ready for use. Another object 5 is to provide a fountain pen in which the pen point and the part in which this is held are slidably mounted so that they may be drawn into the holder when the pen is not in use.

A further object is to provide a dust-proof closure for the aperture through which the pen point is extended. A still further object is to provide means for automatically opening and closing this closure in such a manner that the pen point will not be marred or damaged.

Additional objects are to provide a fountain pen, of the type described, of simple construction, which has no parts easily broken up or apt to get out of order, in which the pen point is securely held in either its operative or inoperative position, which can be made of a size no larger than the ordinary fountain pen, and which can be manufactured and sold at a relatively low cost.

These and various other objects and advantages will be readily understood from the following description and from the accompanying drawing of a preferred embodiment of the invention, in which, however, modifications may be made without departing from the scope of the 30 appended claims. In the drawing

Fig. 1 is a plan view of the pen shown closed;

Fig. 2 is a similar view with the pen extended;

Fig. 3 is a longitudinal sectional view shown with the pen extended;

Fig. 4 is a similar side view shown closed;

Fig. 5 is a side elevation of certain parts used in the pen;

Fig. 6 is an end view of the pen shown with the pen point extended;

Fig. 7 is an end view shown closed; and

Fig. 8 is a cross-sectional view taken on the line 8—8 in Fig. 4.

Referring now to all the views, simultaneously, the pen consists of a holder which is preferably made up of an outer tube 10 and an inner tube 11. The inner tube is firmly secured in the outer tube. A slot 12 is formed in both of these tubes and this slot is preferably provided with a "bayonet" lock 13 at each end. A sleeve 14 is slidably mounted on the holder and is connected, by means of a flat member 15, to the barrel 16 of the pen so that the barrel will slide in the holder when the sleeve is moved up or down. The pen point 17 is mounted in a cap 18

and connected with the customary rubber sack 19, which is contained in the barrel 16.

An opening 20 is formed in the side of the barrel 16 and over this opening a light spring 21 is secured, so that when the pen point is extended, as shown in Fig. 3, this spring will be underneath and aligned with the end of a lever 22 mounted on the holder. As this is a well known filling device, it need not be further described, except to state that in this case the spring and the lever are aligned with each other only when the pen point is extended.

A cap 23 is threaded into the bottom of the holder and extends some distance into the holder. It is provided with a recess 24 and with a slot 25. A plunger 26 is slidably mounted in the recess 24. A short compression spring 27 is secured in the end of the barrel 16, and another compression spring 28 is placed below the plunger.

A bushing 29, having an opening 30, through which the pen point is extended, is rigidly secured in the upper end of the pen and over this opening a lid 31 is hinged. This lid is connected to the plunger 26 by means of a rod 32 which is slidably mounted in a groove 33, cut in the inner member 11 of the holder. The lower end of the rod 32 is bent sidewardly and inserted in a hole 34 drilled in the plunger 26, while the upper end of the rod is pivoted to a pair of lugs 35 mounted underneath the hinge.

The pen operates in the following manner. When the pen is closed, as shown in Figs. 1 and 4, the sleeve 14 is turned so that the member 15 engages in the lower notch 13 in the slot 12. As soon as the sleeve is turned so as to align the member 15 with the slot 12, the springs 27 and 28 tend to slide the barrel in the holder so as to project the pen point through the aperture in the end of the pen. However, as soon as the barrel starts to move, the spring 28 will act and, through the instrumentality of the rod 24, will open the cover ahead of the pen point.

When the pen is extended for use, it will be noted, as previously said, that the lever 22 is aligned with the spring 21 so that the pen may be filled in the usual manner.

When the pen is open and if the sleeve has been turned so that the member 15 is engaged in the upper notch 13, the sleeve is turned and then pulled down, thus drawing the pen into the holder. The spring 28 will maintain the lid in its open position until the spring 27 engages with the plunger 26, after which the tension of this spring will slowly close the lid. Thus the lid cannot

close until the pen point is inside of the holder and out of danger of being marred by the lid.

To adjust the tension of the springs to the right proportions, I preferably drill a plurality of holes 34 in the plunger 26, as plainly shown in Fig. 5.

Having described the invention and its objects, what I claim as new and wish to protect by Letters Patent is:—

- 10 1. A fountain pen of the type described; comprising a holder; a fountain pen barrel slidingly mounted in said holder; a pen point mounted at one end of the barrel; a slot formed in the holder; a sleeve slidingly mounted on the outside of the barrel and rigidly connected to the barrel; one end of the holder closed; an aperture formed in the other end of the holder; a lid, for covering said aperture, hinged adjacent to the aperture; a rod pivoted at one end to said hinge and contained within the holder; the other end of said rod connected to a plunger slidingly mounted in the other end of the holder; a relatively short compression spring inserted in the lower end of the barrel; another compression spring inserted 25 under the plunger; and said springs so proportioned that, when the sleeve is moved in one direction the lid will be opened, by the action of the spring below the plunger, prior to the extension of the pen point through the opening, and when moved in the other direction, the lid will be closed, by 30 the action of the other spring.

2. A fountain pen of the type described; comprising a holder; a fountain pen barrel slidingly mounted in said holder; a pen point mounted at one end of the barrel; a slot formed in the holder; a sleeve slidingly mounted on the outside of the barrel and rigidly connected to the barrel; one end of the holder closed; an aperture formed in the other end of the holder; a lid, for covering 35 said aperture, hinged adjacent to the aperture; a rod pivoted at one end to said hinge and contained within the holder; the other end of said rod connected to a plunger slidingly mounted in the other end of the holder; a relatively short compression spring inserted in the lower end of the barrel; another compression spring inserted under the plunger; said springs so proportioned that, when the sleeve is moved in one direction 40 the lid will be opened, by the action of the spring below the plunger, prior to the extension of the pen point through the opening, and when moved in the other direction, the lid will be closed, by 45 the action of the other spring.

in the other direction, the lid will be closed, by the action of the other spring; and means for locking the pen point in either its extended or distended position.

3. A fountain pen of the type described; comprising a holder; a fountain pen barrel slidingly mounted in said holder; a pen point mounted at one end of the barrel; a slot formed in the holder; a sleeve slidingly mounted on the outside of the barrel and rigidly connected to the barrel; one 10 end of the holder closed; an aperture formed in the other end of the holder; a lid, for covering said aperture, hinged adjacent to the aperture; a rod pivoted at one end to said hinge and contained within the holder; the other end of said 15 rod connected to a plunger slidingly mounted in the other end of the holder; a relatively short compression spring inserted in the lower end of the barrel; another compression spring inserted under the plunger; said springs so proportioned 20 that, when the sleeve is moved in one direction the lid will be opened, by the action of the spring below the plunger, prior to the extension of the pen point through the opening, and when moved in the other direction, the lid will be closed, by 25 the action of the other spring; and means for adjusting the tension of said springs.

4. A fountain pen of the type described; comprising a holder; a fountain pen barrel slidingly mounted in said holder; a pen point mounted at 30 one end of the barrel; a slot formed in the holder; a sleeve slidingly mounted on the outside of the barrel and rigidly connected to the barrel; one end of the holder closed; an aperture formed in the other end of the holder; a lid, for covering 35 said aperture, hinged adjacent to the aperture; a rod pivoted at one end to said hinge and contained within the holder; the other end of said rod connected to a plunger slidingly mounted in the other end of the holder; a relatively short 40 compression spring inserted in the lower end of the barrel; another compression spring inserted under the plunger; said springs so proportioned that, when the sleeve is moved in one direction the lid will be opened, by the action of the spring 45 below the plunger, prior to the extension of the pen point through the opening, and when moved in the other direction, the lid will be closed, by the action of the other spring; and a filling device operable only when the pen point is extended. 50

ANTHONY LO CURTO.
